UNITED STATES PATENT OFFICE.

LUTHER C. CROWELL, OF BROOKLYN, ASSIGNOR TO R. HOE & CO., OF NEW YORK, N. Y.

SHEET-DELIVERY MECHANISM.

SPECIFICATION forming part of Letters Patent No. 339,531, dated April 6, 1886.

Application filed March 28, 1885. Serial No. 160,436. (No model.)

To all whom it may concern:

Be it known that I, LUTHER C. CROWELL, a citizen of the United States, residing at Brooklyn, county of Kings, and State of New York, have invented certain new and useful Improvements in Sheet-Delivery Mechanism, fully described and represented in the following specification, and the accompanying drawings, forming a part of the same.

10 This invention relates, generally, to that class of delivery mechanism which is adapted to operate upon a printed web to sever the same into short lengths or sheets, and fold and deliver said sheets in proper form for distribution as newspapers.

15 It is the object of the invention to provide a mechanism of this character which is capacitated to deliver products of different size or volume, so as to meet the wants of those publishers who desire to issue papers which vary in size with the different days of the week, and also to deliver the product folded to different dimensions, so as to be in suitable form for distribution, either by carriers or by mail.

20 The invention relates particularly to the means by which the mechanism is capacitated to deliver the product folded to different dimensions.

25 The details in the construction of the mechanism in which the invention is embodied, and also its organization and operation, will be hereinafter so fully described and explained as to render all further preliminary description unnecessary to a complete understanding of the invention.

30 In the accompanying drawings, Figure 1 is an elevation of a delivery mechanism embodying the present invention. Fig. 2 is a similar view looking from the right of Fig. 1. Fig. 3 is a plan-view of a portion of the mechanism, showing the web turners around which the sections of the web pass to be directed to the folding mechanism. Fig. 4 is a similar view of the whole mechanism, the web-turners, the frame in which they are mounted, and the brackets upon which this frame is supported being removed. Fig. 5 is a sectional elevation taken upon the line xx of Figs. 1 and 4, the web-turners and the frame in which

they are mounted being omitted. Fig. 6 is a sectional elevation taken upon the line yy of the same figures, the web-turners and frame in which they are mounted being omitted and the folders of the primary folding mechanism shown as adjusted to a different position. Fig. 7 is an irregular cross-section of the machine, the sheet-laying mechanism being omitted, and also the greater part of the supporting frame-work. Fig. 8 is an enlarged sectional elevation of a portion of Fig. 6. Fig. 9 is a diagrammatic plan view illustrating the travel of the webs and sheets through the delivery mechanism when the parts are adjusted to the position shown in Figs. 1 to 5, inclusive. Fig. 10 is a similar view illustrating the travel of the webs and sheets through the delivery mechanism when the parts are adjusted to the position shown in Fig. 6. Figs. 11 and 12 illustrate the condition of the product after it has passed the primary folding mechanism. Figs. 13 and 14 illustrate the condition of the product after it has passed the intermediate folding mechanism. Figs. 15 and 16 illustrate the condition of the product after it has passed the final folding mechanism when said final mechanism is adjusted to the position shown in Figs. 6 and 10; and Figs. 17 and 18 illustrate the condition of the product after it has passed the final folding mechanism when said mechanism is adjusted to the position shown in Figs. 1 to 5 and 9.

35 Referring to said drawings, it is to be understood that the delivery mechanism therein shown as embodying the invention is designed to operate in connection with a printing mechanism which perfects a double-width web, and consists, essentially, of a primary folding mechanism composed of two longitudinal folders, 100 101, arranged one in advance of the other, and in such position that the webs or sheets from both pass between the same pair of rolls, an intermediate folding and severing mechanism composed of a pair of folding and cutting cylinders, 102 103, and a pair of folding-rolls, 104 105, arranged to receive the webs from both of the folders of the primary mechanism, sever them into sheets, and fold the sheets transversely, a final folding mechanism composed of two

40 45 50 55 60 65 70 75 80 85 90 95 100

longitudinal folders, 106 107, arranged side by side, and in such position that each receives the product of one of the folders of the primary mechanism, and a sheet laying or 5 piling mechanism consisting of a rotary carrier or fly, 108, which is arranged to receive and pile the sheets from both the folders of the final folding mechanism.

The intermediate and final folding mechanisms and the sheet-piling mechanism are supported in a suitable frame-work, 110, which does not require specific description, as a frame suitable for the purpose can be designed and constructed by any ordinarily skillful 15 mechanic. The primary folding mechanism is mounted upon a supplemental or auxiliary frame-work, 109, which is so constructed and arranged that it can be adjusted to different positions upon the frame 110, and thereby bring 20 the folders 100 101 into different positions with relation to the other mechanisms. The purpose of this adjustment as well as the particular devices by which it is effected will be hereinafter fully explained.

25 Referring now particularly to Fig. 3, it is to be understood that the web A, after having been perfected by any ordinary form of web-printing mechanism and split into two sections, a' a'' , by an ordinary slitter, located 30 at any convenient point, is let in at the side of the delivery mechanism in such position that the two sections, or, as they will be hereinafter termed, "webs," a' a'' , will pass above a pair web-turners, 90 91, which are arranged in the 35 usual manner, so that in passing around them the two webs are turned at right angles to their previous path of travel before they are presented to the folding and delivery mechanisms. The web-turners 90 91 are supported 40 at their ends on a rectangular frame, 99, (see Figs. 1, 2, and 3,) which rests on brackets 98 rising from the frame 110. The two pairs of brackets 98 at the ends of the frame are connected by cross-bars 97, and the ends of the 45 frame 99, which rest upon these bars, are provided with flanges 96, which lie upon the outside of the bars, and thus prevent the frame 99 from moving lengthwise. The side pieces of the frame 99 are provided at their ends with 50 downwardly-extending lugs 95, through which pass adjusting-screws 94, the inner ends of which impinge against the brackets 98. By this means the frame 99 can be shifted laterally, so as to vary the position of the web-turners 55 with relation to the folders 100 101. The purpose of this will be made clear when the operation of the mechanisms is described. After passing the turners 90 91 the two webs are led around register-rolls 92 93, which are 60 mounted in adjustable bearings in the frame 109 in such manner that they can be shifted in position and thus regulate the travel of the webs, so as to bring the printed pages into proper register with the cutting and folding 65 mechanisms. After passing around the register-rolls 92 93, the webs are led rearward, as indicated by the arrows, to rolls 88 89,

which are also journaled in the frame 109, and located just above the bases of the folders 100 101.

The folders 100 101, as herein shown, are of substantially the same construction as one of the forms shown and described in United States Letters Patent No. 281,619, to which reference is made for a detailed description thereof. They are not, however, provided with tapes, 70 as shown in the Letters Patent referred to, because as the folders are to act upon the webs before they are severed into sheets such tapes are not absolutely necessary, though in some cases 80 it will be found desirable to provide these folders with tapes, and this can be readily done. These folders are arranged one directly in advance of the other, and are supported at their bases upon transverse bars 86 87, which are 85 secured to the sides of the frame 109, and at their points by means of pivoted rods 84 85, which pass through brackets 83, extending downward from the sides of the frame, and are provided with adjusting-nuts 10, by which 90 the points of the folders can be adjusted so as to be brought into proper position with relation to the bite of the rolls 81 82, which constitute the external turners of the folders.

The frame 109, in which the folders 100 101 95 constituting the primary folding mechanism are supported, is, as before stated, made adjustable with relation to the frame 110, in which the other parts of the mechanism are supported, so as to permit these folders to be brought 100 into different positions with relation to the subsequent folding mechanisms. For this purpose the sides of the frame 109 are provided with flanges 80, which rest in bearings 79, formed in the upper part of the sides of the 105 frame 110, while the brackets 83, which connect the side pieces of the frame 109, are provided at their bottoms with bearings 78, which rest upon beams 77, extending from one end to the other of the frame 110, as best shown 110 in Figs. 1, 4, 5, and 7.

To effect the proper adjustment of the frame 109, the rearmost one of the brackets 83 is provided with a nut, 76, in which works a screw-rod, 75, which is journaled in the end 115 of the frame 110, and is provided with a hand-wheel, 74, by which it can be operated so as to move the frame 109 along the beams 77 and bearings 79, and thus shift the position of the folders. The rolls 80 81, which constitute the 120 external turners of the folders 100 101, are, as will be observed, journaled in the frame 110, and are of sufficient length to always co-operate with the folders, no matter into what position they are adjusted, by the movement of 125 the frame 109. After passing around the rolls 88 89, the webs are led downward across the faces of the folders 100 101, and between the rolls 81 82, so that each is folded longitudinally. After leaving the rolls 81 82 the two 130 webs, now folded longitudinally, are led side by side to the cutting and folding cylinders 102 103 of the intermediate folding mechanism. The cylinder 103, which is of a circum-

ference equal to the length of one sheet, is provided with the usual severing-blade, 11, while the cylinder 102, which is of a circumference equal to the length of two sheets, is provided with two co-operating cutting-grooves, 12. Just in the rear of the grooves 12 the cylinder 102 is provided with two sets of impaling pins, 13, which are arranged to be moved in and out through openings in the cylinder, and are mounted upon arms extending from rock-shafts 14, which are journaled in the heads of the cylinder, and are provided with rock-arms 15. (see Fig. 5,) which are operated by a stationary cam, 16, so as to protrude and retract the pins to impale and release the sheets at the proper times, the arms 15 being held to the cam 16 by means of springs, (not shown,) which are arranged in the usual manner.

At the proper points between the cutting-grooves 12 the cylinder 102 is provided with two rotating folding-blades, 17, which are of the common construction, and are mounted upon shafts 18, journaled in the heads of the cylinder and operated to fold the sheets off the cylinder at the proper times by means of cross-heads 19, which engage with a stationary cam, 20, and operate the blades in the usual manner. The folding-rolls 104 105, which co-operate with the cylinder 102 and blades 17, are also of the common form, and are arranged in the usual position with relation to the cylinder. After leaving the rolls 104 105 the two webs, now severed into sheets, pass into the control of a series of tapes, 9, which pass around the roll 104 and a roll, 73, located a short distance in advance of the folding-rolls, and by which they are directed between two series of guides, 21 22, and into the bite of tapes, by which they are conveyed to the folders 106 107 of the final folding mechanism, and thence to the piling mechanism.

The folders 106 107, which constitute the final folding mechanism, are of substantially the same construction as the folders 100 101 of the primary folding mechanism, except that they are smaller in size and have one of their turning edges extended or elongated considerably beyond the other. The purpose of this elongation of one of the turning edges will be made clear when the operation of the mechanism is explained. These folders, instead of being arranged one in advance of the other, so that both co-operate with the same pair of rolls, as is the case with the primary folders, are arranged side by side and provided with separate pairs of co-operating rolls or external turners. It will be observed that as the webs have been severed into sheets before arriving at these folders it becomes necessary that they should be provided with tapes for conducting the sheets over them, and, as here shown, the tapes which operate to conduct the sheets to and over the folders of the final mechanism are so arranged that they also conduct the sheets from these folders to the piling mechanism. The tapes by which this is accomplished consist of six series, 2 3 4 5 6 7,

the arrangement of which will now be described. The series 2, 4, 3, and 7 pass around pulleys 23, located just above and at the ends 70 of the guides 21 22, thence upward around pulleys 24, located at the bases of the folders. From this point the tapes 2 pass downward across the face of the folder 106 and around the longer of its turning edges, and thence 75 inward between the rolls 71 72, which form the external turners of this folder. From the pulleys 24 the tapes 4 pass downward across the face of the folder 106 and around its opposite or shorter turning edge, and thence inward 80 between the rolls 71 72, where they unite with the tapes 2. From the rolls 71 72 the two series 2 4 pass beneath pulleys 25, and thence between pulleys 26 27, at which point they separate, the tapes 2 passing around pulleys 85 28, thence above and for a short distance in contact with the cylinder-fly 108, thence beneath pulleys 29, and outward around pulleys 30, thence upward around pulleys 31, and thence inward around skew-pulleys 32, while 90 the tapes 4 pass upward from the pulleys 27, around pulleys 33, and thence inward around skew-pulleys 34. From the pulleys 24 the tapes 3 pass downward across the face of the folder 107 and around its longer turning edge, and thence 95 inward between the rolls 69 70, which constitute the external turners of this folder, while the tapes 5 pass downward from the pulleys 24, across the face of the folder and around its opposite or shorter turning edge, and thence 100 inward between the rolls 69 70, where they unite with the tapes 3. From the rolls 69 70 both series of tapes pass beneath pulleys 35 and thence between pulleys 36 37, where they separate, the series 5 passing beneath the pulleys 28, around the cylinder-fly, and thence 105 outward around pulleys 38 and upward around pulleys 39, and thence inward around skew-pulleys 40, while the series 3 pass upward around the pulleys 37, thence around pulleys 110 41, and inward around skew-pulleys 42. From the skew-pulleys 32 34 40 42 all of the tapes pass rearward around pulleys 43 and return to the pulleys 23. The tapes 6 7 pass around pulleys 44, located directly beneath the pulleys 23, thence upward past the pulleys 23, and around the pulleys 24, thence downward around pulleys 45, located at different points along the converging inner-sides of the turning edges of the folders, returning around 115 stretching-pulleys 46 to the pulleys 44. The spaces between the pulleys 27 37 and the pulleys 28 are bridged by stationary guides 8, (see Fig. 8,) which co-operate with the tapes 2 5 to convey the sheets from the former to the latter pulleys, while the spaces between the turning edges of the folders and the rolls 71 72 and 69 70 are bridged by stationary guides 47, (see Figs. 4 and 7,) which co-operate with the tapes 2 4 3 5, to convey the sheets from the turning 120 edges of the folders to said rolls.

The cylinder-fly 108 is so positioned with relation to the rolls 71 72 and 69 70 that the distance traveled by the sheets issuing from

between each pair of these rolls before they arrive upon the surface of the fly will be the same, from which it results that the sheets from the two folders 106 107 arrive at the fly 5 at the same time, and thus became associated in pairs as they are taken by the fly, as indicated in Fig. 8. By this means a simple fly is enabled to pile the product of both folders without operating at any greater speed than 10 would be necessary in piling the product of a single folder.

The fly 108, as here shown, is of the same or substantially the same construction as that shown in United States Letters Patent No. 15 281,754, and in my application for Letters Patent filed October 23, 1884, No. 146,256, and consequently needs no specific description. It is provided with three sets of grippers, 48, which are operated by a stationary cam, 49, 20 to take and release the sheets at the proper time, and with co-operating-stops 50, and a slowly-moving apron or series of tapes, 51, by which the sheets are arrested as they are released by the grippers 48 and conveyed away 25 from the fly.

As illustrated in the present case, the various parts of the delivery mechanism just described receive motion as follows: The cylinders 102 103 are connected by gears 52 53, (see Figs. 9 30 and 10,) and the shaft of the cylinder 102 is provided with a gear, 54, (see Fig. 5,) which engages with a gear, 55, upon the shaft of the roll 81, the rolls 81 82 being geared together in the usual manner. The shaft of the cylinder 102 is also provided with a gear, 56, which is connected through intermediates 57 58 with a gear, 59, upon the shaft of the pulleys 44, which gear 59 in turn engages with a gear, 60, upon the shaft of the pulleys 23. The gears 40 56 57 58 are so proportioned that the speed of the tapes 2 3 4 5 6 7, which are driven by the pulleys 23 44, will be greatly reduced from that of the cylinders 102 103, thus allowing the sheets after they have been folded transversely, 45 and consequently reduced one-half in length, to have their speed reduced during their passage through the final folding mechanism and to the piling mechanism. The gear 57 also engages with a gear, 61, which is mounted 50 upon a shaft, 62, which is provided with a bevel-gear, 63, which engages with a similar gear, 64, mounted upon the shaft of the cylinder-fly 108, and the shaft of the fly 108 is also provided with a gear, 65, which engages with 55 a gear, 66, mounted upon the shaft of the pulleys 28. The rolls 71 72 and 69 70 are geared together in the usual manner, but are driven by the tapes 24 and 35. This particular arrangement of the gears for communicating motion to the various parts is not, however, essential, and may be varied according to circumstances. The tapes 51 may be driven by connections with any one of the moving parts. The power may be applied at any convenient point, but will preferably be applied 60 to the shaft of the cylinder 103.

The delivery mechanism hereinbefore de-

scribed is capacitated to deliver the following products folded to the following dimensions, viz: a product consisting of one full sheet 70 folded once transversely and twice longitudinally, or once transversely and once longitudinally; or a product consisting of two full sheets associated together and folded once transversely and twice longitudinally, or once 75 transversely and once longitudinally. The operation of the mechanism in delivering these products is as follows:

When it is desired to deliver a product consisting of one full sheet folded once transversely and twice longitudinally, the frame 109, carrying the rolls 92 88 and 93 89, and the folders 100 101 of the primary folding mechanism will be shifted by means of the screw 75, so as to bring the folders into the position shown 85 in Fig. 6, and indicated in the diagram Fig. 10. The web A, after being perfected by any suitable form of web-printing mechanism and split into the two sections or narrow webs a' , a'' , will be led in at the side of the delivery 90 mechanism, as shown in Fig. 3. The web a' will then be led around the turning-bar 90, and thence around the rolls 92 88 and downward over the folders 100, and between the rolls 81 82, while the web a'' will be led around 95 the turning-bar 91 and thence around the rolls 93 89, and downward over the folder 101, and between the rolls 81 82, as shown in Figs. 4 and 6. In passing over the folders 100 101 and between the rolls 81 82, the webs will be 100 folded longitudinally, as shown in Figs. 5 and 10, and in this condition they will be led side by side between the cutting and folding cylinders 102 103, as shown in Fig. 1, where their leading ends will be impaled by one set of the 105 pins 13, so as to be carried around upon the surface of the cylinder 102. When the cylinder 102 has completed one-half of a revolution the blade 11, coacting with one of the grooves 12, will sever the webs, thus leaving a pair of 110 full sheets folded to the form shown in Figs. 11 and 12 impaled upon the pins, and at the same time the other set of pins, 13, will impale the newly-cut ends of the web, so as to carry them around upon the cylinder 102. The 115 pair of sheets just severed from the webs will be retained by the pins and carried around upon the cylinder until the folding-blade 17, in the rear of the pins upon which the sheets are held, comes into position to coact 120 with the rolls 104 105, when the pins will be retracted so as to release the sheets, and at the same time the blade 17 will be operated so as to fold them off the cylinder and into the bite of the rolls, as shown in Fig. 1. At 125 the end of the next half revolution of the cylinder 102 the blade 13, coacting with the other of the grooves 12, will sever another pair of sheets from the webs, which sheets will, at the proper time, be folded by the other 130 of the blades 17 into the bite of the rolls 104 105, in the manner just described. The sheets now folded once longitudinally and once transversely, and in the form shown in Figs. 13 and

14, will be directed by the tapes 9 between the guides 21 22, and into the bite of the tapes 2 4 6 and 3 5 7, respectively. The sheets will then be carried upward by these tapes over the pulleys 24, and thence downward over the folders 106 107, and between the rolls 71 72 and 69 70, as shown in Figs. 6 and 10.

It will be observed that when the folders 100 101 are in the position shown in Fig. 6, and indicated in Fig. 10, the webs will be delivered to the cylinder 102 in such position lengthwise of the cylinder that the sheets severed from the webs will be carried by the tapes onto the folders 106 107 in such position that their center lines will pass directly over the points of the folders. In passing over the folders 106 107, and between the rolls 71 72 and 69 70, the sheets will receive a second longitudinal fold, which will reduce them to the dimensions shown in Figs. 15 and 16. After leaving the rolls 71 72 and 69 70 the sheets will pass into the control of the tapes 2 4 and 3 5, by which they will be carried forward until they have passed the guides 8, when they will be associated together and pass into the control of the tapes 2 5, by which they will be conducted onto the cylinder-fly 108, as shown in Figs. 6 and 8. As the leading ends of the pair of sheets arrive in proper position upon the fly 108, they will be taken by one of the sets of grippers 48 and carried around upon the fly until they arrive at or near the stops 50, when they will be released by the grippers and allowed to fall onto the tapes 51, as shown in Figs. 6 and 8, to be conveyed away from the machine.

If it is desired to deliver a product consisting of two full sheets associated together and folded as just described, the folders 100 101 will remain in the position shown in Fig. 6, and indicated in Fig. 10; but the web a^2 , after being led around the turning-bar 91 instead of being led around the rollers 93 89 and over the folder 101, will be led forward over the roller 68, and onto the longitudinal folder 100, beneath the web a' , so that the two webs will be associated and folded together in passing over the folder 100 and between the rolls 81 82. The subsequent operations will be the same as already described, except that all of the sheets will pass over the folder 106 of the final folding mechanism. The successive operations upon the product will be the same as shown in Figs. 11, 13, and 15, except that the product will consist of two sheets associated together instead of a single sheet. In this case, of course, the sheets will not be associated together in pairs, as they pass to the fly 108.

If it should be desired to deliver a product consisting of one full sheet folded once transversely and once longitudinally, the frame 109, carrying the primary folding mechanism, will be shifted by means of the screw 75, so as to bring the folders 100 101 to the position shown in Figs. 2, 4, and 5, and indicated in the diagram Fig. 9. The webs $a' a^2$, will be

led around the turning-bars 90 91, rolls 92 88 and 93 89, and over the folders 100 101, and between the rolls 81 82, so as to be 70 folded longitudinally, the same as already described. From the rolls 81 82 they will be led between the cutting and folding cylinders 102 103, where they will be severed into sheets, as indicated in Figs. 11 and 12, and folded transversely and directed between the guides 21 22, the same as already described, and as indicated in Figs. 13 and 14. From the guides 21 22 the sheets, now folded once longitudinally and once transversely, will be taken by 80 the tapes 2 4 6 and 3 5 7, the same as already described, and carried upward to the pulleys 24, and downward over the folders 106 107, and between the rolls 71 72 and 69 70. It will be observed, however, that when the folders 85 100 101 have been shifted, as stated, the webs will be directed onto the cylinder 102 in such position lengthwise of the cylinder that instead of passing to the folders 106 107, with their center lines directly over the points of 90 the folders, they will pass to these folders in such position, as shown in Fig. 2, and indicated in Fig. 9, that one of their edges will pass directly over the points of the folders, thus causing the sheets, instead of being folded longitudinally in passing over the folders, to be simply carried or directed around the longer of the turning edges of the folders, as indicated in Fig. 9, so as to be merely directed between the rolls 71 72 and 69 70, without being folded, thus omitting the second of the longitudinal folds, and causing the sheets to pass into the control of the tapes 2 4 and 3 5, folded to the dimensions indicated in Figs. 17 and 18.

From the tapes 2 4 and 3 5 the sheets will pass 105 into the control of the tapes 2 5, and be associated together in pairs and delivered to the fly 108, and deposited upon the tapes 51, the same as already described, and as indicated in Fig. 8.

If it should be desired to deliver a product consisting of two full sheets folded to the dimensions just described, the web a^2 , after being led around the turning-bar 91, will be led over the roll 68, and onto the folder 100 beneath the web a' , so as to be associated therewith, the same as already described, after which the further operations of severing the associated webs into sheets, and folding and delivering the sheets, will be the same as just 115 described, except that all of the sheets will pass around the longer of the turning edges of the folder 106, the folder 107 being idle.

If it should be desired to capacitate a delivery mechanism of this character to deliver 125 a product of a volume greater than two full sheets associated and folded together, as described, it may readily be done by equipping the cylinders 102 103, in the manner shown in my application for Letters Patent filed January 13, 1882, No. 50,017, so that when desired 130 two or more pairs of sheets may be associated together, and folded between the rolls 104 105, or the same result could be readily accom-

plished by interposing any of the well-known forms of sheet-associating mechanism between the rolls 81 82 and the cylinder 102, in which case the cutting cylinder 103 will be dispensed with, and suitable severing mechanism provided for severing the webs into sheets before they arrive at the associating mechanism. In either of these cases the sheet - associating mechanism would be rendered inoperative whenever a product consisting of one or two sheets was to be produced.

A product consisting of two full sheets might be produced by leading the web a' to the folder 100 and the web a^2 to the folder 101, the same as when single sheets are delivered, and then causing succeeding sheets severed from each web to be associated in either of the ways just described before they pass to the intermediate and final folding mechanisms.

It is also to be observed that it is not necessary that the cutting mechanism and the sheet-associating mechanism (if the delivery mechanism is provided with a sheet-associating mechanism) should be located so as to operate upon the webs after they have passed the primary folding mechanism. The cutting mechanism may be located so as to sever the webs into sheets before they pass to the folders 100 101 of the primary folding mechanism, and the sheets so severed from the webs may be associated before they pass to the primary folding mechanism, and this association of the sheets may be effected by associating the webs and then severing them into sheets to produce a two-sheet product, or by associating the webs, then severing them into sheets, and then associating the pairs of sheets to produce a larger product, or by severing the unassociated webs into sheets and then associating the succeeding sheets from each web to produce a product of two or more sheets. In any of these cases the primary folding mechanism will, of course, be provided with suitable taping to conduct the sheets to and over the folders 100 101 and to the intermediate folding mechanism. The manner of arranging tapes so as to accomplish this result is well known in the art, and therefore need not be described.

Although the primary and final folding mechanisms, as herein shown, each consists of two longitudinal folders, it is of course to be understood that these mechanisms may consist of three or more folders, (the intermediate mechanism being made of sufficient length to co-operate therewith,) if it is desired to operate upon a web of sufficient width to produce three or more of the narrow webs, as $a' a^2$. In such case as this a product consisting of three or more (depending upon the number of webs) full sheets associated and folded together may be produced by leading all of the webs to and over one of the folders of the primary mechanism, and then operating upon them in the manner already described for producing a product consisting of two full sheets. It is also to be understood that the primary and final folding mechanisms may each consist of only a single

longitudinal folder. In such case a product consisting of two or more full sheets can be produced by associating two or more webs before they pass over the single folder of the primary mechanism, or by associating two or more of the succeeding sheets severed from a single web, either before or after it passes over the folder. To produce a product consisting of a single sheet, in such case a web of the width of one of the webs a' or a^2 will be printed upon.

It is also to be remarked that it is not necessary that the web or webs should be led in at the side of the delivery mechanism, as shown in the present case. The web or webs may be led in at the end of the mechanism, if preferred. In such case one of the webs will pass directly to one of the folders of the primary folding mechanism, while the other will be led around two turning bars, so as to be transferred laterally to a position either above or below the other web, so as to be led to the same or the other of the folders of the primary folding mechanism, according as it is desired, or not, to associate the webs, as shown in my application for Letters Patent filed January 13, 1882, No. 50,017.

In producing newspapers it sometimes happens that it is desirable to vary the size of the product or paper within narrower limits than a full sheet, and this can only be done by decreasing the size of the sheet printed. It is very difficult to diminish the length of the sheet in the direction of its travel through the machine; but it is not difficult to diminish the length of the sheet widthwise of the machine, as all that is necessary to accomplish this is to omit one or more columns from the sides of the forms if the columns lie circumferentially of the printing-cylinders, or shorten the columns if they lie longitudinally of the cylinders, and use a web of correspondingly-reduced width. When, however, the width of the web or the sections or narrow webs into which the web is split is diminished, it becomes necessary, in order to present the webs to the folders of the primary folding mechanism in such position that their center lines will pass directly over the points of the folders and thus cause them to be folded in the middle, to shift the position of the turning bars around which the webs pass. For this purpose the bars 90 91 are mounted in the adjustable frame 99, as shown. When the webs $a' a^2$ are of full width, as shown in Fig. 3, the frame 99 will be adjusted so as to bring the bars into the position shown in said figure, thereby, as will be seen, presenting the webs to the folders 100 101 in such position that their center lines will pass directly over the points of the folders and the webs be folded longitudinally in their centers. When, however, the webs are reduced in width, so as to make the sheets severed from the webs of less length crosswise of the direction of their travel, the screws 94 will be operated so as to shift the frame 99 and bars 90 91 to the position

shown by dotted lines in Fig. 3, or to some intermediate position, and thus cause the webs to be presented to the folders in such position that, although they are of reduced width, their center lines will still pass over the points of the folders, and they will thus be folded evenly on their centers.

If it should be desired to deliver a product consisting of half-sheets instead of full sheets, the mechanism will be provided with ordinary slitters, located, preferably, at or near the points of the folders 100 101, which will be so arranged that when desired they can be thrown into operation and split the webs a' a^2 upon the fold-line as they pass over the folders. The half-sheets thus produced will then be folded transversely by the cylinder 102 and rolls 104 105, and will then pass to the folders of the final folding mechanism, and be either folded longitudinally or pass these folders without being folded, depending upon the position of the folders of the primary folding mechanism, after which they will be delivered to the fly 108, the same as full sheets. When half-sheets are being produced, the two webs a' a^2 will preferably be led to the same folder of the primary folding mechanism, so that when they are split and severed into sheets and folded by the cylinder 102 they will be folded together into lots of four half-sheets each, which will facilitate the counting of the product. When producing half-sheets, the primary folding mechanism will preferably be adjusted to the position shown in Figs. 2 and 5, so that the half-sheets will not be folded in passing over the folders of the final folding mechanism.

In conclusion it is to be remarked that in many of its details the delivery mechanism herein described may be varied greatly without departing from the essential features of the present invention. The intermediate severing and folding mechanisms, instead of being of the form shown, may be of any other approved form which is adapted to impart a transverse fold to the sheet; or, if it should be desired that the delivery mechanism should impart but one or two folds, instead of two or three folds to the sheets, then this intermediate mechanism may be entirely dispensed with, the longitudinally-folded webs being led directly from rolls 81 82 to the folders of the final folding mechanism, after passing which they will pass to a cutting mechanism, and be severed into sheets and then delivered to the piling mechanism, and in such case the folders of the final mechanism need not be provided with tapes; or if the intermediate folding mechanism is omitted, the webs may be severed into sheets between the primary and final folding mechanisms, in which case the final mechanism will be provided with tapes, or they may be severed into sheets before reaching the primary mechanism, in which case both the primary and final mechanisms will be provided with tapes.

It is also to be remarked that the folders of

the primary and final mechanisms need not necessarily be of the form shown, but may be of any other suitable construction for this class of folders—such, for example, as the other construction shown in Letters Patent No. 281,619, or in the several Letters Patent heretofore granted to me for improvements in this class of folders; or they may be of the construction shown in my application for Letters Patent No. 120,116, filed February 8, 1884.

It is also to be remarked that the sheet laying or piling mechanism need not be of the construction shown herein, but may be of any other approved form—such, for example, as that shown in Letters Patent No. 269,021; or, if preferred, each of the folders of the final mechanism may be provided with a separate piling mechanism, in which case the taping of these folders will be modified accordingly, and in any case the taping of these folders may be different from that shown without departing from the invention, the particular arrangement of the tapes shown being adapted merely for the purpose of illustration, and because it is believed, all things considered, to be the best for the purpose.

It is also to be remarked that the piling mechanism will preferably be provided with suitable means by which the sheets, as they are delivered, will be divided into lots containing some predetermined number, so that they can readily be delivered without the necessity of counting, and such counting mechanism may be of any approved construction, but will preferably be of the form shown in my application for Letters Patent filed October 6, 1884, No. 144,808.

From the foregoing it will be seen that the present invention does not consist so much in improvements in the specific mechanisms of which the delivery apparatus is composed as in the combination with said mechanisms of means whereby one or more of them is rendered adjustable, or in the modification of the construction of some of them, by which they are rendered adjustable with relation to each other.

The combination of two folding mechanisms, arranged to act upon the web or sheet in succession, and the second of which is a longitudinal folder, said mechanisms being adjustable with relation to each other, so that the web or sheet may be received by the second in position to be folded thereby or in position to be simply guided by it without being folded, is not herein claimed, as this subject-matter is claimed in my prior application, filed April 17, 1884, No. 128,238. Neither do I herein claim the combination, with turning bars arranged to turn and associate webs, of a longitudinal folder for folding the associated webs and a web-severing mechanism, or a web-severing and transverse folding mechanism, arranged parallel with the printing-cylinders. Neither do I herein claim the combination, with a plurality of longitudinal folders,

of web turning and associating mechanism arranged to turn a plurality of webs which are running side by side, so as to change their direction of travel and bring them into line, whereby they may be led to different folders to be folded separately or associated, and led to the same folder to be folded together, as these subjects-matter are claimed in another application.

10. What I claim is—

1. The combination of two longitudinal folders, the first of which is adjustable, so that it can be shifted to different positions whereby the product delivered from it will pass to the second in position, to be folded thereby, or in position to pass said second folder without being folded, all substantially as described.

2. The combination, with a folding mechanism composed of a plurality of longitudinal folders, of a second folding mechanism composed of a like number of longitudinal folders, the folders of said first mechanism being adjustable, so that they can be shifted to different positions whereby the product delivered from them may pass to the folders of the second mechanism in position to be folded thereby, or in position to pass said second folders without being folded, and a web-associating mechanism, all substantially as described.

3. The combination, with a folding mechanism composed of a plurality of longitudinal folders mounted in a movable frame, of a second folding mechanism composed of a like number of longitudinal folders arranged to receive and act upon the product after it leaves the first folders, the frame carrying the first folders being capable of such a movement that the product may pass to the second folders either in position to be folded thereby or in position to pass said folders without being folded, all substantially as described.

4. The combination, with a longitudinal folder, a transverse folding mechanism, and a

second longitudinal folder, the three being arranged to act upon the product in the order named, and said first longitudinal folder being adjustable, so that it can be shifted to different positions whereby the product delivered from it may pass to the second longitudinal folder in position to be folded thereby, or in position to pass said second folder without being folded, all substantially as described.

5. The combination, with a folding mechanism composed of a plurality of longitudinal folders, of a second folding mechanism composed of a corresponding number of longitudinal folders, an interposed transverse folding mechanism capacitated to receive and act upon the product of all of the folders of the first mechanism, and means whereby the folders of the first mechanism may be shifted in position, so that the product may be delivered to the folders of the second longitudinal folding mechanism in position to be folded thereby or in position to pass said folders without being folded, all substantially as described.

6. The combination, with a longitudinal folder, of a web-turner for turning the web before it is presented to the folder, said web-turner being adjustable, so that webs of different widths may be properly presented to the folder, all substantially as described.

7. The combination, with a plurality of longitudinal folders, of a plurality of web-turners mounted in a movable frame and arranged to turn the webs and present them to the folders, and means for adjusting the position of the frame carrying the turners, all substantially as described.

In testimony whereof I have hereunto set my hand in the presence of two subscribing witnesses.

LUTHER C. CROWELL.
